UNITED STATES PATENT OFFICE.

HARRY B. PRUDEN, OF NEW CASTLE, PENNSYLVANIA, ASSIGNOR TO POWDERED COAL ENGINEERING AND EQUIPMENT COMPANY, OF CHICAGO, ILLINOIS, A CORPORATION OF DELAWARE.

SIPHONIC FEEDER FOR COMMINUTED MATERIAL.

1,165,444.

Specification of Letters Patent. Patented Dec. 28, 1915.

Application filed April 9, 1914. Serial No. 830,653.

To all whom it may concern:

Be it known that I, HARRY B. PRUDEN, a citizen of the United States, residing at New Castle, in the county of Lawrence and State 5 of Pennsylvania, have invented certain new and useful Improvements in Siphonic Feeders for Comminuted Material, of which the following is a specification.

This invention relates to devices for feeding finely comminuted material and has special reference to a device for feeding such material by siphonic action.

The principal object of the invention is to provide an improved device wherein the material will be fed from a hopper or the like by siphonic action in a manner similar to drawing off water from a tank by a siphon.

A second object of the invention is to provide an improved form of siphon for delivering such material.

With the above and other objects in view the invention consists in general of certain novel details of construction and combination of parts hereinafter fully described, illustrated in the accompanying drawings, and specifically claimed.

In the accompanying drawings, like characters of reference indicate like parts in the several views, and Figure 1 is a view showing one form of the device as applied to such a mixture as is shown and described in my co-pending application filed February 28th, 1914 and bearing the Serial No. 821,787. Fig. 2 is a view of a modified form of siphonic beater. Fig. 3 is a view of a second modification thereof.

In the device shown in Fig. 1 there is provided a hopper 10 having an open bottom 11 whereto is secured a boot 12 so that the material in the hopper is fed down into the boot. Depending into this boot is an end 13 of a siphon tube 14 which extends down to the inlet side 15 of an injector 16 provided 45 with a jet of high pressure air through a pipe 17 controlled by a valve 18.

In the form shown in Figs. 2 and 3 there is provided a hopper 19 having a closed bottom 20 and in each of these forms there is 50 provided the siphon 21 having an end 22 extending down into the hopper. In all of the forms just described there is provided an agitator for the comminuted material con-

sisting of a pipe ring 23 provided with suitable perforations 24. This pipe ring is 55 spaced below the inlet end of the siphon and surrounds the axis of said inlet end. Furthermore the ring 23 is provided with high pressure air through a tube 25 controlled by a suitable valve 26. This valve is best seen 60 in Fig. 3.

In the form shown in Fig. 2 there extends upward through the bottom of the hopper 19 a jet pipe 27 which is controlled by a valve 28. The upper end of this jet pipe 65 terminates in a nozzle 29 which extends upward into the mouth of the siphon 21, the nozzle being spaced from the walls of said siphon.

In the form shown in Fig. 3 there is provided a T 30 between the valve 26 and the ring 23 and branching from this T is a jet pipe 31 which extends laterally inward and terminates in an upwardly extending nozzle 32 arranged in all respects similar to the 75 nozzle 29.

Now, if it be supposed that one of these hoppers is filled with comminuted material and air supplied through the pipe 25 then it will be seen that material at the bottom of 80 the hopper is agitated and becomes a mixture of air and the comminuted material of the nature of a dust cloud so that suction on the pipe 14 will cause this dust cloud to flow through said pipe. In like manner the blast 85 from the jet nozzles 29 and 32 in the other form act similar to the suction and may be used to assist the same. Thus in all of these forms there is provided means creating a dust cloud at the mouth of the siphon and 90 means for causing said dust cloud to flow through the siphon. There has thus been provided a simple and efficient device of the kind described and of the character specified.

It will be obvious that many minor changes may be made in the form and construction of this invention without departing from the material principles thereof. It is not therefore desired to confine the invention to the exact form herein shown and described, but it is wished to include all such as come properly within the scope claimed.

Having thus described the invention, what is claimed as new, is:

1. In a device for feeding comminuted

material, a hopper, a pipe extending downward into the hopper and terminating in spaced relation to the bottom thereof, a high pressure air pipe extending up through the 5 bottom, of the hopper into the first mentioned pipe, a ring pipe surrounding the high pressure pipe below the mouth of the first mentioned pipe, said ring pipe being provided with a multiplicity of perforations in 10 the top thereof, and a high pressure supply pipe connected to the ring pipe to supply air thereto.

2. In a device for feeding comminuted material, a hopper, a pipe extending downward into the hopper and terminating in spaced relation to the bottom thereof, a high pressure air pipe entering the hopper, a perforated ring pipe carried by the high pressure pipe and disposed above the hopper bottom 15 and beneath the end of the first named 20 tom and beneath the end of the first named

pipe and means for supplying air under pressure to the high pressure pipe.

3. In a device for feeding comminuted material, a hopper having a cup-shaped bottom, a pipe extending downward into the 25 hopper and terminating in spaced relation to the bottom thereof, a high pressure air pipe entering the hopper, a perforated ring pipe carried by the high pressure pipe and disposed above the hopper bottom and beneath the end of the first named pipe and means for supplying air under pressure to the high pressure pipe.

In testimony whereof I affix my signature in presence of two witnesses.

HARRY B. PRUDEN.
